DESIGN FOR A BATHING SPRAY PADDLE

Anthony Ferrera, Detroit, Mich.

Application May 20, 1946, Serial No. 129,895

Term of patent 3½ years

(Cl. D91—1)

To all whom it may concern:

Be it known that I, Anthony Ferrera, a citizen of the United States and a resident of the city of Detroit, county of Wayne, and State of Michigan, have invented a new, original, and ornamental Design for a Bathing Spray Paddle, of which the following is a specification, reference being had to the accompanying drawings, forming a part thereof, in which drawings,

Fig. 1 is a plan view of a bathing spray paddle embodying my new design;

Fig. 2 is a side elevation of said paddle; and

Fig. 3 is an end view of said paddle.

I claim:
The ornamental design for a bathing spray paddle, as shown.

ANTHONY FERRERA.
